UNITED STATES PATENT OFFICE.

FREDERICK T. SNYDER, OF OAK PARK, ILLINOIS.

THREE-PHASE ELECTRIC FURNACE AND METHOD OF OPERATING SAME.

1,279,928.

Specification of Letters Patent. Patented Sept. 24, 1918.

Application filed March 11, 1918. Serial No. 221,609.

To all whom it may concern:

Be it known that I, FREDERICK T. SNYDER, a citizen of the United States, residing at Oak Park, in the county of Cook and State 5 of Illinois, have invented a certain new and useful Improvement in Three-Phase Electric Furnaces and Methods of Operating Same, of which the following is a full, clear, concise, and exact description.

- 10 In cases where electric furnaces have been operated heretofore from a three-phase current source of power the arrangement commonly employed has been to connect a carbon electrode to each of the three phases usually through a transformer resulting in the use of three electrodes. These electrodes project through the roof of the furnace into the melting chamber and terminate a short distance above the molten bath. Under 15 these conditions the resistance between the ends of the three electrodes is substantially equal. Hence the currents flowing in each of the three phases are substantially equal and the phases are well balanced.
- 20 Each electrode consumed during the operation of an electric furnace, however, constitutes an additional source of expense and for this reason it is desirable to reduce the number of electrodes employed as far as 25 consistent with other factors to be considered. Attempts have been made in the past to reduce the number of upper electrodes to two, using one bottom contact which latter does not require frequent renewal. For this 30 purpose, however, it has been necessary to transform the three-phase current to two-phase current before it is supplied to the furnace. In one case the three-phase current has been transformed to two-phase current in such manner that the two phases are 35 90° apart. In another case two phases are produced which are 120° apart. To these and other systems, however, various objections have been made based on the fact that 40 45 the balance between the three phases is not as complete as it should be; or that special transformers are required; or that other inherent difficulties exist.

The objects of the present invention are to 50 provide means and a method whereby three-phase current may be supplied directly to an electric furnace having two carbon electrodes and a bottom contact; to accomplish this result without special transformers and

in general with a minimum amount of special equipment; and to take advantage of the heretofore objectionable fact that a reactance is necessary in order to stabilize the arc and that the unavoidable reactance of the furnace shell has distorted the current balance in the systems heretofore proposed and to so design and arrange this unavoidable shell reactance with reference to the furnace and its circuit as to cause it to perform an additional and advantageous function in reducing the voltage between each upper electrode and the bottom contact as compared with the voltage between the two electrodes, thereby equalizing the flow of current.

70 Other advantageous features will be apparent from the following description taken in conjunction with the drawings in which—

Figure 1 is a diagram of the complete circuit connections in the preferred form of 75 the invention.

Fig. 2 is a simplified diagram of the secondaries of the transformer and other furnace connections, and

Figs. 3 and 4 are further diagrams illustrating phase relations.

The structure of the electric furnace proper may vary in accordance with different requirements, but consists preferably of refractory walls 1 of cylindrical form reinforced by a cylindrical steel shell 2. Suitable electrodes 3, 4 consisting preferably of carbon are adjustably supported above the furnace and extend through the roof of the furnace projecting into the melting chamber 90 with their lower ends at substantially equal distances above the molten bath. A suitable bottom contact 5 is also provided which is preferably a metallic water cooled structure, the details of which, as well as other structural details of the furnace, form no part of the present invention.

95 The furnace is supplied with current from any suitable source of polyphase current preferably a three-phase source supplying 100 the three-wire circuit 6, 7, 8. Three transformers 9, 10, 11 are connected to the power circuit preferably in the manner shown. The transformers may be of standard construction employing either the well known delta or Y connections. Said transformers 105 comprise primary coils 12, 13, 14 respectively and secondary coils 15, 16, 17 respec-

tively, said secondary coils consisting preferably of two windings in series.

One end of each of the secondary coils 15 and 17 are connected at a common point 18, the other ends being connected at the points 19 and 20 with the terminals of the third secondary coil 16. A suitable conductor 21 connects the junction 18 with the bottom contact 5 of the furnace, said circuit including a suitable switch 22 and a reactance 23. This reactance, which is the main reactance, is inserted at this point for a double purpose. It stabilizes the two arcs, each of which is in series with it, through the circuit to the bottom contact and through the molten bath. Also it is so designed as to cause a voltage drop in the current phase through the bottom contact equal to the voltage drop in each arc, so that with equal currents flowing through the two electrodes and the bottom contact there will be an equal voltage drop from the bath to the external current supply along each of the three circuits.

An additional conductor 24 extends from the juncture 19 to one of the upper electrodes 3 and a similar conductor 25 extends from the juncture 20 to the other upper electrode 4. These two circuits include also reactances 26 and 27. These reactances include the inherent and unavoidable reactance of the circuits, to which is added such further reactance as may be necessary to make the two arc circuit currents, equal the contact circuit current when the main reactance has been adjusted to the amount required to stabilize the arcs at the arc voltage used. The reactance 23, on the other hand, constitutes the main reactance and consists primarily of the furnace shell and such additional reactance as may be required under given conditions to accomplish the stabilizing of the arcs previously referred to and at the same time balance the three currents.

The arc stabilizing reactances have heretofore been located in the circuits of the two separate phases containing the two arcs, whereas in the present case, I use the single reactance located in the circuit of the third phase and in series with each of said arcs. Since a stabilizing reactance is necessary in any case, I accomplish by this novel arrangement the desirable results sought by taking advantage of what have heretofore been objectionable characteristics and so employing them as to render their use highly advantageous.

The diagram Fig. 3 indicates the open circuit voltage between the three terminals representing the two upper electrodes and the bottom contact. This voltage may be assumed to be 150 volts. In other words, the voltage between the two upper electrodes will be 150 volts and the voltage between each upper electrode and the bottom contact will be

150 volts. When the current flows it is controlled largely by the resistance of the arcs. It is apparent, therefore, that in the absence of special compensating means much more current will flow from each electrode to the bottom contact through one arc in each case than will flow from one upper electrode to the other through two arcs in series. The three phases, therefore, will be unbalanced. In my present invention this excess current through the contact is reduced and made equal to the current through the two electrode circuit by the voltage drop of the main reactance.

In the diagram Fig. 4, the same terminals are also shown and the junction point 28 represents the molten bath. It will be seen that the angle between the three phases is 120° in each case.

The stabilizing reactance composed chiefly of the furnace shell is at an angle to the two phases including the arcs instead of being in the phase with each arc. The two arcs are thereby stabilized with one reactance. If the current begins to increase in either arc, the cross section of the arc increases, thereby reducing its resistance and further increasing the flow of current through said arc. A portion of this increase current flows through the main reactance increasing the voltage drop through said reactance. This reduces the component of voltage available for the arc in question by increasing the angle between the two arc phases as indicated in dotted lines, the juncture point moving from 28 to 29, for example. As a result, the flow of current through said arc is decreased. If, on the other hand, the current through either arc tends to decrease below the normal value the reverse operation takes place, the current through the arc increases (see lowered junction point 30), and normal conditions are therefore automatically restored. This arrangement, therefore, provides for an inherent regulation stabilizing both arcs with a single reactance, also giving balanced loads on all of the three phases of a three-phase circuit and permitting three-phase current to be supplied directly to the furnace, said phases being 120° apart.

With the operating voltage values assumed in Fig. 4 it will be seen that the three arms of the star represent approximately a voltage drop of 63 volts. Assuming that the shell reactance under given conditions corresponds to a voltage drop of 41 volts, it will be necessary to provide additional reactance equivalent to a voltage drop equal to the difference between 63 and 41, which is 22 volts, represented by reactance 23. In order to balance the phases it will be necessary therefore to adjust the reactances 26, 27 to values, also corresponding to 22 volts. The two arcs are then adjusted to correspond

to a voltage drop of 41 volts each, the figures chosen being purely arbitrary. It is desirable to make the reactances 23, 26 and 27 as small as possible, preferably zero. If the reactance volts of the shell are not equal to the arc voltages then the system will be unbalanced but may be balanced by making a relative adjustment of the reactances 26, 27.

It will be noted in Fig. 1 that structurally the electrodes, 3, 4 are adjustably supported by two electrode cranes 31, 32. The circuit to said electrodes from the conductors 24, 25 is through or adjacent to said cranes. In order to render the electrode circuits non-inductive the said cranes are arranged adjacent and parallel, whereby the currents flowing through said cranes, being partially in opposite directions, the inductance of one partially offsets the inductance of the other. During the operation of an electric furnace, it is sometimes desirable to reduce the power supplied thereto. With the present arrangement, this reduction can be effected simply by opening the switch 22 in the circuit of the bottom contact. Such opening cuts off two of the three equally loaded current paths, reducing the power input to one-third of the full load. A reduction to approximately one-sixth of the full power may be accomplished at the same time by changing the primary connections of the transformers from delta to star. In a properly designed furnace, the metal may be kept hot with one-sixth of the full load input.

Where it has been attempted heretofore to obtain a balanced three-phase load with a furnace of this type, *i. e.*, one having two upper electrodes, a higher voltage is used between the said electrodes than between each electrode and the bath. This higher voltage tends to cause leakage of current through the hot roof, thereby decreasing the load available for effective work in the furnace. With my delta arrangement, the voltage between the two electrodes is no higher than the voltage between each electrode and the bath, whereby for a given load and current, the leakage through the roof can be kept at a minimum.

Having thus described my invention, what I claim as new and desire to secure by Letters Patent of the United States is:

1. The method of operating electric furnaces having current paths of different resistances, from a source of polyphase current, which consists in providing reactance in the path of lowest resistance of such amount as to automatically equalize the currents flowing in the different phases of said polyphase system.

2. The method of operating electric furnaces having two upper electrodes and a bottom contact which consists in supplying three-phase current directly to the furnace

terminals and reducing the flow of current between each upper electrode and said bottom contact by means of a reactance in the phase of said bottom contact whereby the three phases are balanced.

3. The method of operating electric furnaces having two upper carbon electrodes and a bottom metallic contact from a source of three-phase current, which consists in reducing the current flow between each upper electrode and said bottom contact to balance the flow through the two arcs in series.

4. The method of operating electric furnaces having upper electrodes and a bottom contact which consists in providing a reactance in series with said bottom contact sufficient to cause a voltage drop equal to the voltage drop through the arcs between each of said electrodes and a bath in contact with said contact.

5. The method of operating multi-phase electric arc furnaces which consists in stabilizing the arc by means of a voltage drop which is out of phase with the current causing said arc.

6. The combination with a source of three-phase current, of an electric furnace having two upper electrodes and a third terminal in conducting relation with the molten bath, each of said three terminals being directly connected with one of said phases.

7. The combination with a source of three-phase current, of an electric furnace having two upper carbon electrodes and a bottom metallic contact, three transformers connected to said three-phase circuit and connected also to said three terminals, the three phases supplied to said furnace being 120° apart.

8. The combination with a source of constant potential polyphase electric current of an electric furnace having current paths of different resistance and with reactance in the paths of lower resistance of such amount as to substantially equalize the currents flowing in the different phases of said polyphase system.

9. The combination with a source of three-phase electric current of an electric furnace having two electrodes and a bottom contact, each connected to a different phase of said current source, the current path through said contact being of higher reactance than the path through the two electrodes.

10. The combination with an electric furnace having three terminals including a bottom contact, of secondary transformer coils connected to each other and to said three terminals and a stabilizing reactance connected between said transformer coils and said bottom contact to stabilize two arcs in the furnace and to balance the current in the three phases.

11. In combination, a three-phase circuit,

an electric furnace having two upper electrodes and a bottom contact, transformers connected to said three-phase furnace and to the three terminals of said furnace, and a 5 reactance connected in the phase which includes said bottom contact.

12. An electric furnace having two upper electrodes and a bottom contact, three secondary transformer coils connected in delta, 10 an arc stabilizing reactance connected in series between one juncture of said transformer coils and said bottom contact and further reactance in series between the other two junctures of said secondary coils and 15 said upper electrodes.

13. An electric furnace having a plurality of electrodes and a bottom contact, said furnace having a shell of magnetic material adapted to form a reactance in the circuits 20 passing through said contact.

14. An electric furnace having a plurality of electric circuits in which the sum of the reactance ohms and the resistance ohms for the different circuits are substantially equal.

25 15. An electric furnace having a plurality of electric circuits, the reactance of one of the circuits being substantially lower than the reactance of another of the circuits.

16. In combination, a three-phase circuit, 30 an electric furnace having two upper electrodes and a bottom contact connected with said circuit, providing two arcs between said electrodes and the metal bath, a reactance in one phase of the furnace circuit and the 35 said arcs being arranged in the other two phases of said furnace circuits.

17. The combination with an electric furnace having a plurality of electrodes and a bottom contact, of circuits supplying said 40 electrodes and said contact, said electrode circuits being close together and separated from the circuit supplying said contact.

18. An electric furnace with a plurality of electrodes and a bottom contact in combi-

nation with electric circuits supplying said 45 electrodes and contact, the circuits through said electrodes which do not pass through said contact being non-inductive as compared with the circuits through said contact.

19. The combination of an electric fur- 50 nace having a plurality of electrodes and a bottom contact of a switch in the circuit to said contact, the opening of said switch serving to reduce the power supply to said furnace for constant position of the electrodes. 55

20. The combination with an electric furnace having three terminals providing for two arcs, of a source of polyphase current therefor, and a single reactance stabilizing said two arcs, the current through said arcs 60 differing in phase.

21. The combination with an electric arc furnace comprising an upper electrode and a bottom contact, of a source of current therefor, the drop in voltage in the circuit 65 of said contact being equal to the voltage drop across said arc stream.

22. The combination with an electric furnace having two upper electrodes and a bottom contact, of a source of polyphase current 70 for the two arcs between said electrodes and the bath, the drop in voltage due to the reactance of the circuit of said contact being equal to the voltage drop across each of said arc streams. 75

23. The combination with an electric furnace having two upper electrodes and a bottom contact, of a three-phase supply circuit and three transformers connected to said supply circuit and to the furnace terminals 80 corresponding to said electrodes and said contact, the connection being such as to maintain a balanced load on said supply circuit.

In witness whereof I hereunto subscribe 85 my name this ninth day of March A. D., 1918.

FREDERICK T. SNYDER.
